(57) CLAIM

(22) Filed: **Apr. 4, 2000**

The ornamental design for a slide door to change over the air path in an air conditioner, as shown and described.

(30) Foreign Application Priority Data

DESCRIPTION

Oct. 29, 1999 (JP) 11-29643

FIG. 1 is a perspective view of the top and rear of a slide door to change over the air path in an air conditioner showing our new design;

(51) LOC (7) Cl. **23-04**

FIG. 2 is a side elevational view thereof;

(52) U.S. Cl. **D23/354**

FIG. 3 is a rear elevational view thereof;

(58) Field of Search D23/351, 354,

FIG. 4 is a top plan view thereof;

D23/386, 387, 391, 392; 165/41, 43; 49/41,

FIG. 5 is a bottom plan view thereof;

40, 275, 350, 353, 336, 361, 362, 341;

FIG. 6 is a front elevational view thereof; and,

454/143, 152, 154, 155, 284, 313, 316,

FIG. 7 is a view similar to FIG. 1 with the slide door in an

330, 334; D25/48

intermediate position.

The components shown in phantom lines are for background purposes only and do not form part of the claimed design.
